UNITED STATES PATENT OFFICE

LAWRENCE E. DICKSON, OF CHICAGO, ILLINOIS

CUSHION FOR GOOGLES

Application filed October 11, 1928. Serial No. 311,779.

The present invention relates to a removable cushion for goggles or the like, so formed that it may be secured to the eye rims of goggles and remain firmly secured without the necessity of sewing or clamping means.

Among the objects of my invention are the following:

To provide the eye cups of goggles with a cushion adapted to be removably secured to the eye cups without the necessity of stitching or clamping parts.

To create a securing means in a cushion for goggles so that the cushion may be firmly applied to the eye rims of the goggles, without the need for any further securing means.

To afford a sanitary cushion for goggles which may be affixed or removed by the wearer without the need of stitching or the use of clamping members.

To provide cushion for goggles which may be easily, quickly and inexpensively replaced without any further act than the removal and replacement thereof.

To produce a cushion for goggles readily replaceable, which will be inexpensive to manufacture, simple to construct it, durable of wear, and such other objects, advantage and capabilities as will later more fully appear and which are inherently possessed by my invention.

My invention further resides in the combination, construction and arrangement of parts illustrated in the accompanying drawings, and while I have shown a preferred embodiment of my invention, I wish it understood that the same is susceptible of modification and change without departing from the spirit of my invention.

Referring to the drawings—

Fig. 1 is a front view of my cushion as applied to goggles; Fig. 2 is a side view and Fig. 3 a rear view of the same.

Fig. 4 is a cross-sectional view taken on line 4—4 of Fig. 3.

Fig. 5 is a perspective view, partly in section of my cushion, showing interior of the same.

My invention more in detail comprises a body member 1 found in circular shape. Said body member is preferably moulded when

sponge rubber is employed, but any suitable cushioning or padding material may be used and formed in any desired manner. Said body member 1 has a face portion 2, rounded inside and outside side portions 3 and 4, and a back or rear portion 5.

The back portion is slit completely around with a groove 6 running into the inside of the body member as clearly shown in Fig. 4.

The groove 6 forms a straight side wall 60 running on the inside of the side portion 3.

The groove 6 is also cut so as to form another side wall 8 or the inside of the side portion 4. The side wall 8 is also straight for a portion of its distance and runs parallel to side wall 7 until it reaches a point approximately illustrated in Fig. 4.

The groove 6 then runs at right angles and slightly forwardly or in a direction away from the face and toward the outside 70 wall 3 so that side wall 8 has a hook portion 9.

In placing the body member 1 on the eye piece frame 10 of goggles 11, it will be noted that said eye piece frame 10 has on its peripheral border an edge rolled outwardly to form a projecting flange 12. This projecting flange 12 is inserted into the groove 6 as far as 9 as clearly shown in Fig. 4. This permits the hook portion 9 of the side wall 8 80 to close around the projecting flange 12 and securely hold or lock the body member 1 to the eye piece frame 10.

Heretofore, where goggles have had cushioning members like body member 1, the padding material was sewed to the eye frames. This meant that the cushion was not readily removable, and could not be replaced by the wearer without going to the added effort of having the new cushion sewed to the frame. 90 Where the sewing method was not employed, it has heretofore been necessary to use clips, attached to the frame for clamping over the cushion. Other buttoning, riveting or clamping means have been resorted to, requiring extra parts on the frame and cushion.

Where goggles are used, for safety, and as a protection for men in hazardous or dangerous pursuits or wherever it is desirable to 100

use goggles as a precaution, for the protection of the eyes, there has been a necessity for a removable cushion which is readily replaceable.

5 It will readily be seen that my device may be immediately applied in actual use and at once firmly anchored to the eye piece frame. As the cushion remains on the frame, the anchor or hook portion 9 settles to more 10 firmly grip the project-flange 12 and thus insures a firm and certain grip.

My cushion may be removed at the will of the wearer and another cushion replaced without the need for sewing or operating, 15 clamping or other fastening means. The 10 acts of affixing or removing my cushion are in themselves sufficient.

Having thus described my invention, I claim:

20 1. A goggle cushion formed as a ring, a groove in one face of the ring, the walls of said groove parallel a portion of their depth, an offset in one wall of said groove, and thin flanges extending from the edges of said 25 groove.

2. A goggle cushion comprising an annular elastic body having an inwardly extending groove formed in one face thereof, and an offset in one wall of said groove, said offset substantially at right angle to said wall and extending forwardly.

3. A goggle cushion comprising an annular elastic body having an inwardly extending groove formed in one face thereof and an offset in one wall of said groove, said offset substantially at right angle to said wall.

In witness whereof, I hereunto subscribe my name to this specification.

LAWRENCE E. DICKSON.
